CLAIM

The ornamental design for a GPS tracking pod assembly, as shown and described.

DESCRIPTION

FIG. 1 is a top perspective view of a GPS tracking pod assembly showing my new design;

FIG. 2 is a top view thereof;

FIG. 3 is a left view thereof;

FIG. 4 is a right view thereof;

FIG. 5 is a bottom view thereof;

FIG. 6 is a front view thereof;

FIG. 7 is a rear view thereof;

FIG. 8 is a bottom perspective view thereof; and,

FIG. 9 is a bottom perspective view of a GPS tracking pod assembly, shown in a configuration of use.
